CONDIMENT HOLDER

Lawrence Heebner, Reading, Pa.

Application June 14, 1937, Serial No. 148,214

1 Claim. (Cl. 65—45)

This invention relates to condiment holders, and its general object is to provide a holder that includes at least two separate compartments, one for containing salt and the other pepper, with 5 perforated caps for closing the compartments, as well as valve means for alternately covering or closing the perforations, so that either condiment can be individually dispensed from the holder, and the valve means can be easily actuated for the purpose set forth.

A further object is to provide a condiment holder of the character referred to, that is simple in construction, inexpensive to manufacture, and extremely efficient in operation, use and service. 15 This invention also consists in certain other features of construction and in the combination and arrangement of the several parts, to be hereinafter fully described, illustrated in the accompanying drawing and specifically pointed out in 20 the appended claim.

In describing the invention in detail, reference will be had to the accompanying drawing wherein like characters denote like or corresponding parts throughout the several views, and in which:

25 Figure 1 is a vertical sectional view taken through the condiment holder which forms the subject matter of the present invention, with the valve means disposed to close the perforations of the cap of one compartment, in full lines, and to 30 close the perforations of the cap of the other compartment in dotted lines.

Figure 2 is a sectional view taken approximately on line 2—2 of Figure 1.

Figure 3 is a top plan view of the holder.

35 Figure 4 is a sectional view taken approximately on line 4—4 of Figure 1.

Figure 5 is a perspective view of the holder with the valve means removed.

Figure 6 is a side view of the valve means detached from the holder.

Referring to the drawing in detail, the reference numeral 1 indicates the body of my holder which as shown is of substantially oval shape in outline, and includes an enlarged lower portion 45 tapered inwardly as at 2, toward the bottom 3, which has formed thereon and depending therefrom a bead 4 about the outer edge thereof, to provide the base for the holder.

From the enlarged lower portion, the body is 50 curved inwardly and thence merges into neck portions 5 of the respective compartments 6 and 7 that are provided by a partition 8 rising centrally from the bottom, and which merges at its upper end into a web 9 between the neck portions, 55 as clearly shown in Figure 1.

It will be noted that the web 9 from its juncture with the partition 8, is outwardly inclined upon opposite sides thereof, as at 10 for directing the contents of the compartments to the outer ends of the necks 5 thereof, and the outer end portions 5 of the necks are exteriorly threaded for the purpose of threadedly receiving caps 11 for closing the same, the caps being provided with perforations 12 and the perforations of one cap are larger than those of the other, it being obvious that the 10 cap having the larger perforations is for the neck of the compartment for containing salt and which is indicated by the reference numeral 7, while the other cap is for the neck of the compartment for containing pepper and which is indicated by the 15 reference numeral 6.

Formed on and rising centrally from the web 9 for disposal between the mouth portions of the necks 5 is a lug 13 having a bore extending longitudinally adjacent the upper end thereof to 20 act as a bearing for a pivot pin 14 for the valve member of my holder, which includes a central straight portion 15 having apertured ears 16 depending from the ends thereof and mounted on the pivot pin 14 as clearly shown in Figure 4. 25 Formed on and extending from opposite sides of the central straight portion 15, are disk shaped flaps 17 that are substantially of the same diameter as the caps 11 and it will be noted that the flaps 17 are disposed at an upward angle or inclination from the straight portion, so that when one flap is disposed upon its cap to close the perforations thereof, the other is elevated above its cap to allow for the free passage of the condiment through the perforations thereof, therefore 30 it will be obvious that the flaps act as valve means for controlling the dispensing of the condiments from the compartments, and either is held in closed position by the thumb of the user during the use of the holder in dispensing the contents 40 therefrom.

It will be noted that the body together with the neck portions thereof, partition, web and lug are shown as being formed into a single unit, preferably from glass, but they may be made from 45 any material suitable for the purpose and connected together in any suitable manner, and the caps and valve means are made from any suitable material.

It is thought from the foregoing description that 50 the advantages and novel features of the invention will be readily apparent.

It is to be understood that changes may be made in the construction and in the combination and arrangement of the several parts, provided 55

that such changes fall within the scope of the appended claim.

What I claim is:

A condiment holder comprising a hollow body of substantially oval outline, and including an enlarged lower portion and a bottom, a supporting bead depending from the bottom, said body being curved inwardly from the lower portion for restricting the same between its ends, a partition 10 dividing the body into equal compartments, a neck for each compartment and formed on and rising from the inwardly curved portion of the body at opposed outward inclinations with respect to each

other, a perforated closure for each neck, said partition being enlarged at its upper end to provide a web forming the inner portions of the walls of the necks, a bearing lug rising from the web between the necks, valve means including a straight central portion, apertured ears depending from the opposite ends of the central portion and pivotally secured to the lug, and opposed flaps of equal diameter formed on the central portion and extending at an upward angle therefrom for alternately engaging the closures for controlling the perforations thereof accordingly.

LAWRENCE HEEBNER.
